UNITED STATES PATENT OFFICE.

TEIJI KOTATO, OF NEW YORK, N. Y., ASSIGNOR TO MORIMURA BROS. INC., OF NEW YORK, N. Y., A CORPORATION OF JAPAN.

DESIGN FOR A PLATE OR SIMILAR ARTICLE.

58,600.

Specification for Design.

Patented Aug. 2, 1921.

Application filed January 31, 1921. Serial No. 441,433. Term of patent 7 years.

To all whom it may concern:

Be it known that I, TEIJI KOTATO, a subject of the Emperor of Japan, residing in the city, county, and State of New York, have invented a new, original, and ornamental Design for a Plate or Similar Article, of which the following is a specification, reference being had to the accompanying drawing, forming part hereof.

The figure is a plan view of one of the pieces, to wit: the dinner plate, of a china dinner set, showing my new design.

I claim:

The ornamental design for a plate or similar article, as shown.
